DOOR CHECK AND CLOSER.

1,414,996.

Specification of Letters Patent. Patented May 2, 1922.

Application filed July 1, 1921. Serial No. 481,891.

To all whom it may concern:

Be it known that I, CHARLES W. PARKER, a citizen of the United States, residing at Kansas City, in the county of Jackson and 5 State of Missouri, have invented certain new and useful Improvements in Door Checks and Closers; and I do declare the following to be a full, clear, and exact description of the invention, such as will enable others 10 skilled in the art to which it appertains to make and use the same, reference being had to the accompanying drawings, and to the figures of reference marked thereon, which form a part of this specification.

15 This invention relates to a door check and closer adapted to mechanically close an open door in such a manner that the door will be prevented from slamming.

The device contemplates the provision of 20 means whereby the door will be closed with sufficient force to enable the latch bolt to move into latching position but the closing movement will be checked sufficiently to prevent a too sudden closing or jar of the door 25 against the door frame.

Devices for accomplishing this general result are well known and they generally involve the utilization of heavy oils or air.

The inherent difficulty with the proper 30 performance of such door checks is that where liquids, such as oils and the like, are used, the viscosity of the oils change due to varying temperatures and atmospheric conditions so that they require more or less personal attention to adjust them for the 35 constantly changing atmospheric conditions.

Where air is used, the piston leathers become hard and readily leak after the checks have been in use for a while so that they 40 do not perform as efficiently after they have been in use for any considerable period as they do when first installed.

It is the purpose of my invention to provide a door check and closer which will depend solely upon mechanical means for effecting the closing movement of the door and likewise provide the necessary retardation to eliminate liability of the door slamming.

50 My invention also contemplates a novel construction whereby the necessity of using screws and the like may be eliminated and the cost of manufacture maintained at a minimum on account of simplicity of parts 55 and ease of assembly.

It is also an object of my invention to provide a simple construction of door check and closer whereby the same may be conveniently reversed from right to left or arranged so that it may be secured to permit the arms to 60 operate in vertical planes.

The novel arrangement of the mechanism as well as the details of construction embodied in the form of my invention selected for illustration will be specifically described 65 hereinafter, reference being had to the accompanying drawings, in which—

Fig. 1 is a perspective view of a door check and closer constructed in accordance 70 with my invention.

Fig. 2 is a disassociated perspective view of the mechanism minus the operating arm and lever for connection to the door frame.

Fig. 3 is a cross sectional view through the casing and cover, the spring being shown in 75 elevation.

Fig. 4 is a detail perspective view of one end of the operating shaft and the brake band support.

Fig. 5 is a vertical, longitudinal, sectional 80 view through the device with the parts assembled.

Fig. 6 is a cross sectional view showing the position of the parts when the door is moving into open position, and 85

Fig. 7 is a like view showing the position of the parts when the door is moving into closing position.

Referring now to the drawings by numerals of reference:

1 designates a housing or case for the mechanism and it is shown as tubular in form, having oppositely disposed wings or bracket members 2 and 3 by means of which the housing or case may be fastened to the 95 top rail of the door. The bottom of the tubular housing 1 is closed by a removable cover plate 4, which has side flanges 5 and 6 to engage the grooves 7 and 8 on the housing whereby the plate 4 may be secured in 100 position and said plate is further provided with a central opening 9, adapted to be closed by a pivoted shutter 10, pivoted thereto as at 11 so that access to the interior of the housing may be had without removing 105 the cover plate 4, as will be apparent hereinafter.

The top of the tubular member or housing 1 is closed by a cover 12, having a central shaft-receiving opening 13 surrounded by 110

a polygonal boss 14 whereby a wrench may be applied to turn the cover plate for the purpose of adjusting the motor spring which actuates the door closer.

5 The cover 12 is provided with a downwardly extending peripheral flange 15 having a plurality of slots 16 therein, to be engaged by a vertically slidable detent 17, shown as a bolt in the vertical slot 18 of the 10 housing (see Fig. 2).

The cover 12 is also provided with inwardly projecting pins 19 and 20, which may be introduced into the peripheral groove 21 through the vertical slots 22 and 15 23 so that when the pins 19 and 20 are out of alignment with the slots 22 and 23, the cover will be held against displacement but will be permitted to turn about the axis of the housing member 1.

20 Depending from the lower face of the cover plate 2 are two lugs 24 and 25, spaced apart to provide a slot 26 to receive the lip or bent end 27 of a coil spring 28 which constitutes the actuating motor for effecting the 25 closing of the door. The coil spring 28 has at its inner end a lip or angular projection 29, which may engage in the longitudinal slot 30 on the shaft 31, which projects through the opening 13 and which is provided with a mutilated portion having a flat 30 face 32 to be received by the mutilated socket 33 on the crank arm or lever 34, having a pivotal connection with the link 35 as at 36, the link being adapted to be fastened to the 35 door frame by the ball and socket connection 37. The link is shown as consisting of two members 38 and 39, having adjustable screw threaded connection, as shown in Fig. 1, but the specific construction of the link 40 constitutes no part of my invention, such links being well known in the ordinary door check construction.

The lever 34 is held on the shaft 31 by a nut 40, as will be clearly apparent by reference to Figs. 1 and 5.

The coil spring 28 is shown as provided with a band 41 to prevent it from uncoiling beyond a determined amount.

On one end of the shaft 31 is a brake band 50 carrier and brake actuator support, shown as comprising a disk 42, having spaced flanges 43 and 44. The flanges 43 and 44 are provided with openings 45 and 46 in which the bolt 47 and the head 48 respectively are 55 guided. The bolt 47 is rigid with the head 48 and its free end is adapted to bear against an arcuate spring 49, the ends of which lie in the notches or grooves 50 and 51 of the respective brake band members 60 52 and 53, supported upon the flanges 43 and 44 through the medium of the pins 54 and 55 for the band member 52 and 56 and 57 for the member 53. The band is slotted for the pins 54 and 56 so that they may move 65 outwardly, swinging on the pins 55 and 57

when the bolt 47 is urged against the spring 49 through the actuator element 58, shown as a roller in a recess 59 and adapted to ride upon the incline or cam face 60 of the head 48. The roller 58 will be urged against the 70 inner face 61 of the housing 1 by the springs 49 and if desired, this spring may be augmented by a coil spring 62 about the bolt 47, one end of which bears against the flange 43 and the other against the nut 63 adjacent to 75 the threaded portion 64 which engages the head 48, it being apparent that by turning the nut 63 the distance between the outer end of the bolt 47 and the cam 60 can be increased or diminished, varying the tension 80 upon the spring 49 and by reference to Fig. 5, it will be apparent that the tension on 49 may be varied by swinging the cover plate 10 to uncover the opening 9 so that a wrench may be introduced through the bottom of the 85 casing 1 without disturbing any of the other mechanism.

It will be apparent that when the parts are properly assembled and the door is swung to open position, the roller 48 will 90 drop into the deep portion of the recess 59, as shown in Fig. 6 so that the door may be opened without any resistance offered by the check other than that required to wind up the spring 28. When the operator releases 95 the door, the shaft 31 will turn in an opposite direction under the influence of the stored-up energy of the spring so as to tend to move the door to closing position. The roller 48 will ride up on the high portion of 100 the cam or incline 60, as shown in Fig. 7, slightly reciprocating the head 48 and bolt 47 against the bowed spring 59 so as to expand the brake band members 52 and 53 against the inner face of the housing so that 105 while the spring is urging the door to closing position, the band is offering resistance, it being understood, however, that the force of the spring will preponderate over the resisting effect of the brake so that the door 110 will move to closing position at a retarded speed and it will continue to move until the roller 48 rides into the depression 65 when the brake will be inoperative.

The door will at this time, however, be 115 almost closed so that its acceleration, due to the unretarded spring, will just be sufficient to move it into latching engagement, the brake being off at this time.

By reference to Fig. 7, it will be seen that 120 there are two depressions, one designated 65 and the other 65', the depression 65' serving in the same way as 65 when the mechanism is reversed; that is, when the bolt 47, head 48 and complementary parts are in diametrically opposite positions to that shown 125 in the present drawings, it being sometimes desirable to reverse the parts on account of conditions encountered.

When the door is opened again, the roller 130

48 will run down into the deep portion of the groove 59, as shown in Fig. 6, so that the door can be readily opened, winding up the spring and storing enough energy in it 5 to move the door to closing position as soon as it is released. The roller will then run up into the shallow portion of the groove, as shown in Fig. 7, to again apply the retarding brake, as will be well understood.

10 It is to be observed that there is slight play between the brake band members 52 and 53 and the pins 54 and 56 so that they may readily expand and it is also to be observed that the tension on the spring can 15 be varied by sliding the detent 17 toward the bottom of its slot 18 and turning the cover 12 either to decrease the tension or increase the tension the required amount and then moving the detent 17 into one of the 20 slots 16, which happens to be opposite the slot 18.

Liability of the cover accidentally becoming removed during this time will be eliminated by the pins 19 and 20, which will 25 ride in the groove 21.

Attention is also called to the fact that appropriate brake facings may be provided so that there will be an efficient braking effect when the roller 48 rides into the shallow portion of the groove 59 and that any appropriate material may be used.

It will be apparent from the foregoing that a device constructed in accordance with my invention will efficiently function 35 as a door check and closer without the necessity of employing either air or liquid and as a result, the disadvantages of the use of such mediums will not be encountered since the operation of the various parts are purely 40 under mechanical control and in no wise depend upon air or liquid mediums which are liable to leak or vary the performance of the check and closer due to changes in viscosities, resulting from atmospheric variations.

What I claim and desire to secure by Letters-Patent is:

1. In a door check and closer, the combination with a spring-actuated door closer, a 50 retarding means comprising a split brake band, a brake band expander, and a longitudinally movable bolt for actuating the expander during the rotation of the door closer in one direction.

55 2. In a door check and closer, the combination with a rotatable spring-actuated door closer, a retarding means comprising a fixed member, an expansible brake band to frictionally engage the same, a brake band ex-

50 panding, a longitudinally movable bolt for actuating the expander, and a cam-actuated means for imparting movement to the bolt.

3. In a door check and closer, a cylindrical casing, a spring-actuated door closer in said casing, a split brake band carried thereby, a transversely located, longitudinally movable bolt, means actuated by the bolt for expanding the band, a head on the bolt having a cam groove, and a roller in the groove for imparting longitudinal movement to the bolt and head.

4. In a door check and closer, the combination with a spring-actuated door closer, means for varying the tension of the spring, means for retarding the movement of the 75 door closer, the second mentioned means comprising a split band, a bowed spring for expanding the band, a bolt having movement to cause the spring to function, a head on the bolt having a cam groove, a roller 80 in the cam groove, and a fixed member over which the roller moves and with which it is in constant contact.

5. In a door check and closer, a cylindrical casing, a spring-actuated rotatable door 85 closer, a split band carried thereby, an expander for said split band comprising a bowed spring, the opposite ends of which exert thrusts against the respective end portions of the split band, a bolt bearing 90 against the central portion of the spring, a head having a cam groove, and a roller in the groove bearing against the inner wall of the casing.

6. In a door check and closer, the combination with a cylindrical housing, a spring-actuated rotatable door closer in the housing, a split band carried by said door closer, a bolt supported thereby, a band expander controlled by the bolt, a cam head on the 100 bolt, and a roller co-operating with the cam head to bear against the inner face of the housing.

7. In a door check and closer, the combination with a cylindrical housing, a 105 spring-actuated rotatable door closer in the housing, a split band carried by said door closer, a bolt supported thereby, a band expander controlled by the bolt, a head on the bolt having a cam groove, and a roller in 110 the cam groove bearing against the inner face of the housing, said housing having a roller-receiving notch to receive the roller to release the pressure against the spring actuator.

In testimony whereof I affix my signature.

CHARLES W. PARKER.
